Specification for Design.

Patented June 20, 1916.

Application filed February 16, 1916. Serial No. 78,784. Term of patent 14 years.

To all whom it may concern:

Be it known that I, JULIUS ROEVER, a citizen of the United States, residing in the city of New York, county of Queens, and State of New York, have invented a new, original, and ornamental Design for a Reproducer, of which the following is a specification, reference being had to the accompanying drawings, forming a part thereof.

Figure 1 is a front elevation of the re-

producer showing my design. Fig. 2 is a rear elevation thereof, and Fig. 3 is a side elevation of the reproducer.

I claim:—

The ornamental design for a reproducer as shown.

JULIUS ROEVER.
